UNITED STATES PATENT OFFICE.

SIGMUND LISKOW, OF CINCINNATI, OHIO, ASSIGNOR OF ONE-HALF TO HENRY SWAY,
OF CINCINNATI, OHIO.

ADJUSTABLE BRACKET AND SHELF.

Application filed August 1, 1921. Serial No. 488,982.

To all whom it may concern:

Be it known that I, SIGMUND LISKOW, a citizen of the United States, and a resident of the city of Cincinnati, in the county of Hamilton and State of Ohio, have invented 5 certain new and useful Improvements in Adjustable Brackets and Shelves, of which the following is a specification.

The object of my invention is to produce 10 an adjustable shelf or bracket which can be cheaply manufactured, is very simple in construction and is highly efficient in use, and which possesses a marked degree of utility. It is made from flat bands of iron 15 but may be made of wire or metal strips of any shape or contour, and these strips or bands are united together so that they can readily be assembled from a disassembled or knock-down condition to form brackets, 20 shelves, holders, retaining receptacles and supporting means for hats, caps, bundles, boxes or the like or for the holding of books, sheet music, flat paper articles and the like.

They can be used under pianos or like 25 musical instruments for holding music and the like; in connection with automobile tops on the inside thereof, for holding all kinds of articles and bundles, hats, coats, jackets, and any other article used by the occupant 30 of the machine; they can be placed on desks, bookcases, tables, or on any other article of this kind or class, where a shelf or bracket can be conveniently employed. When not in use they can be folded or knocked-down. 35 They can be assembled into many specific forms for various uses, and their features and advantages will readily become apparent from a perusal of the following specification.

40 In the accompanying drawing forming a part of this specification:

Fig. 1, is a view in perspective of one of the sections of my new adjustable shelf or bracket, with its connecting arm partly extended,

45 Fig. 2, is a perspective view of the completed bracket or shelf,

Fig. 3, is a plan view of same connected to some object (shown in broken dotted lines), the same being folded or knocked-down or disassembled,

50 Fig. 4, is an end view looking at one of the sections to illustrate construction,

Fig. 5, is a perspective view of my new

shelf or bracket assembled provided with 55 double instead of single sections,

Fig. 6, is a plan view of device shown in Fig. 5, in a knock-down or disassembled form, and

Fig. 7, is a view of the shelf or bracket 60 shown in Fig. 5, holding and supporting a hat, said hat shown in dotted lines.

The bracket or shelf is composed of two spaced sections or parts, composed of one or more arms 1, carrying at each end upwardly or outwardly extending uprights 2 and 3. The arms 1, each have pivotally connected thereto at points 4 cross arms 5, which are pivotally connected so that they will swing. In Figs. 5, 6, and 7, the cross arms are both shown pivoted on one of the arms 1 and one passes over the other so that they will readily swing without interference.

One of the arms 5 is provided with an 75 engagement button or stud 6 and the arms 5 with recesses as 7; the recesses 7 passing over and engaging the neck of the buttons or studs 6, to hold or lock the sections together when assembled; they can be disengaged when it is desired to disassemble or knock-down the device. In Figs. 5, 6, and 7, the buttons or studs are only on one of the arms 1.

In Figs. 1, 2, 3, the extensions 2 are provided with holes 8 and the extensions 3, at the opposite end of the arms 1, are provided with swinging connecting brackets as 9 pivotally connected to swing on the extensions 3 at point 10—and are provided with holes as 12, through which nails or screws may pass, tacks or screws as 13 passing through the holes 8 (see Fig. 3). In Figs. 5, 6, and 7 each of the arm extensions 2 and 3 carry such pivoted brackets as 9. 95 I may arrange these brackets 9 and use a greater or less number thereof as may be necessary to properly suspend or fasten the shelf or bracket in any particular place or position.

100 In Figs. 5, 6, and 7, I show two arms as 1 having extensions as 2 and 3, however, not carrying cross arms as 5 or their connections; these arms 1 and their extensions 2 and 3 swing on the other set of such arms and extensions, and are pivoted thereon on extensions 2 and 3, at pivotal point 9, the same pivotal point at which the brackets 9 are

pivoted; it may be stated that by reason of this pivotal connection point described the upper or outer set of arms and extensions swings on the other set, so that said 5 swinging set of arms and extensions may be used as a retaining or holding element, (see Fig. 7 particularly). I will now describe some ways of using my improved adjustable bracket and shelf.

- 10 When out of use and in a disassembled or knock-down form and out of the way, the parts are as shown in Fig. 3, where they are shown in connection with the bottom of a piano or like article marked 20; the screws 15 13 are screwed into the side of the frame and the screws which pass through holes 12 are screwed into the bottom of the article; the arms 1 and extensions 2 and 3 will then swing on the pivotal points 10 and on the 20 screws 13, so they can be pulled down as shown in Fig. 2, and the cross arms 5 made to engage on the stud 6 and form a bracket or shelf as shown in said Fig. 2, upon which the articles can or may be placed; when it 25 is desired to disassemble or knock-down the device, the cross arms 5 are disengaged with the studs 6 and swung over on the arms 1 enabling each section to be swung up as shown in Fig. 3.
- 30 The device just described can be placed on the inside of an automobile top and similarly operated, or placed on any other article desired.

The device, shown in Figs. 5, 6, and 7, is 35 similarly operated; in other words, it is fastened by the brackets 9 and can swing thereon into the position shown in Fig. 5, and the upper set of swinging arms can be moved up and down, when disassembled and moved 40 up out of the way it will appear as shown in Fig. 6; in the end view, shown in Fig. 7, the device is shown holding a hat, shown in dotted lines; the dotted lines also show the extensions 2—2 on the upper swinging 45 arm swung downward, shown in dotted lines in a position for holding or retaining a hat; of course any other article can be placed therein.

These adjustable shelves or brackets can

be made of any shape, and they may be made 50 small for use in connection with small articles, and they may be made large and long, as for example: they may be made as wide, approximately, as an automobile top on the inside so that they will extend entirely across 55 and hold a great number of articles.

It will be noted that the device, when not in use, can be swung up out of the way, and when it is desired to use the same, the parts can be readily swung down and connected. 60

I may use as many cross arms as desired, and pivot and connect them between the sections in any desired practical manner, and the device may be connected to the article to which it is to be attached in any form 65 found practicable.

I do not wish to limit myself to the precise construction herein shown, but may modify the same to some extent.

What I claim as new and my invention and 70 desire to secure by Letters Patent is:

1. A device of the character described formed of two sections, each section formed of an arm, said arms provided with end extensions, connections between the arms for 75 detachably connecting them together and each arm provided with an auxiliary swinging arm attached to the extensions and means for connecting the device to a support so that it will swing to open or to close and to 80 a knock-down form.

2. A device of the character described formed of two sections, each section comprising an elongated arm provided with end extensions and means for detachably connecting the two arms together to form a shelf or bracket and means for suspending the same upon an article rendering the two sections capable of swinging opposite directions, and said connecting means between 85 the arms capable of being swung out of the way, or of being swung to connect said sections.

In testimony whereof, I affix my signature at Cincinnati, Ohio, this 16th day of July, 95 1921.

SIGMUND LISKOW.
